F. B. Perkins

UNITED STATES PATENT OFFICE.

F. B. PERKINS, OF ROXBURY, MASSACHUSETTS.

IMPROVEMENT IN HOISTING-MACHINES.

Specification forming part of Letters Patent No. 42,595, dated May 3, 1864.

To all whom it may concern:

Be it known that I, F. B. PERKINS, of Roxbury, in the county of Norfolk and State of Massachusetts, have invented a new and Improved Hoisting-Machine; and I do hereby declare that the following is a full, clear, and exact description of the same, reference being had to the accompanying drawings, making a part of this specification, in which—

Figure 1 is an elevation of a hoisting-machine made according to my invention; Fig. 2, a vertical section of the same, taken in the line $x x$, Fig. 1; Fig. 3, a plan or top view of the same.

Similar letters of reference indicate corresponding parts in the several figures.

This invention relates to a new and improved hoisting-machine, designed for elevating and lowering goods in warehouses, and for other similar or analogous purposes.

The invention consists in the means employed for operating the platform or receptacle on which the goods to be elevated and lowered are placed, said means being composed of racks attached to posts, between which the platform or receptacle works, pinions, worm-wheels, and screws, which are combined with the platform and are put in motion by an endless belt or other suitable means.

To enable those skilled in the art to fully understand and construct my invention, I will proceed to describe it.

A represent two vertical posts, which are firmly secured, at a proper distance apart, in any proper way; and B B are two racks, which are attached to the inner sides of the posts A A. These racks are double ones—that is to say, teeth are cut on the two opposite sides of each rack-bar, as shown clearly in Fig. 2.

C represents a platform, which is fitted between the two posts A A, and allowed to move freely up and down. This platform has an upright, D, attached to each end of it. These uprights are directly opposite the racks B B, and are provided with cross-heads c c', in which are the bearings of two shafts, E E, said bearings being near the ends of the cross heads. On the ends of the shafts E E there are placed pinions F, which gear into the racks B, a pinion being at each side of each rack-bar, as shown in Figs. 2 and 3. On each shaft E there is fitted a worm-wheel, G, into which screws H H gear. These screws have

their threads in reverse positions, one being a right and the other a left thread, and the worm-wheels G have their teeth cut to correspond each with the thread of the screw which gears into it. The screws H are on a shaft, I, the bearings b of which are in the cross-head a', and on the shaft I, at about its center, there is placed a pulley, J, around which an endless belt or chain, K, passes, said belt or chain also passing over a pulley, L, at the upper part of one of the posts A, and around a pulley, M, which is placed on a shaft, N, at the lower part of one of the posts A, as shown in Fig. 1.

From the above description it will be seen that by rotating the shaft N motion will be communicated to the endless belt or chain K, and the screw-shaft I rotated by said belt or chain, which passes entirely around the pulley J. The screws H H and worm-wheels G G communicate motion to the shafts E E and pinions F, and the latter, in consequence of gearing into the racks B, raise or lower the platform C, according to the direction in which the shaft N is turned. By this simple arrangement several advantages are obtained: First, the platform C will not fall, even when loaded, in case of the breaking of the belt or chain K; second, no connecting-gearing is employed, nor any gearing which runs with any great degree of velocity, consequently much wear and tear and noise are avoided.

I do not claim separately any of the parts herein shown and described, irrespective of their combination and arrangement for the purpose specified.

I claim, therefore, as new and desire to secure by Letters Patent—

The employment, in a hoisting-machine, of racks and pinions having teeth of the character shown in the drawings, and which gear with each other, in combination with a platform and with worm screws and worm-wheels, or their equivalents, the mechanism being actuated by an endless belt or chain, or by other equivalent means of imparting motion, and being constructed and operating substantially as described.

F. B. PERKINS.
